UNITED STATES PATENT OFFICE.

GEORGE M. WILLIS, OF CHICAGO, ILLINOIS.

ELECTRIC HORN.

1,076,181.

Specification of Letters Patent.

Patented Oct. 21, 1913.

Application filed June 20, 1913. Serial No. 774,749.

To all whom it may concern:

Be it known that I, GEORGE M. WILLIS, a citizen of the United States, residing at Chicago, in the county of Cook and State of Illinois, have invented a certain new and useful Improvement in Electric Horns, of which the following is a full, clear, concise, and exact description, reference being had to the accompanying drawings, forming a part of this specification.

My invention relates to electric horns and more particularly to horns which are operated by alternating electric current, although certain features of my improved horn may be readily incorporated in direct current horns.

The object of my invention is to produce a device of the class mentioned which is simple in construction, efficient in operation and one which may be economically manufactured.

The horn herein described and subsequently claimed is designed to be constructed almost entirely of sheet metal and the various parts of the horn are so arranged that after the various parts are assembled the armature forming a part of the device is non-adjustable. This is a desirable feature inasmuch as a device of this class which is to be sold at a comparatively low price must not be subject to tampering and the consequent derangement if the same is to give satisfactory service.

My invention is more fully set forth in the following description and is illustrated in the accompanying drawings in which—

Figure 1 is a longitudinal sectional view of the horn of my invention, and Fig. 2 is a fragmentary sectional view taken on the line 2—2 of Fig. 1.

Similar reference numerals refer to similar parts throughout.

In the drawings I have shown the usual amplifier at 3, which projects into a diaphragm chamber which is formed by two dish-shaped corrugated sheet metal members 4 and 5 which have their annular flanges 6 secured together by rivets 7. Disposed between the dish-shaped sheet metal members 4 and 5 and secured by means of rivets 7 is a sounding diaphragm 8. By making the dish-shaped members 4 and 5 of sheet metal and corrugating the same as shown, I am able to secure a rigid structure, at the same time using a minimum amount

of materials in the construction of my horn. It is desirable to have the diaphragm chamber comparatively large, as shown in the drawings, in order to secure a mellow tone. Horns of the general type to which the present invention relates have in the past been subject to objection because of the shrill and oftentimes harsh sound produced by the horn, and this has usually been due to the fact that the diaphragm chambers have been too shallow and of the wrong shape.

Disposed behind the sounding diaphragm and disposed coaxially therewith is a flat spring or spring diaphragm 9, which is secured to the dish-shaped member 5 by means of rivets 10, these rivets also serving to support a coil housing 11 which is disposed against the back of the dish-shaped member 5. It will readily be seen that when the parts are assembled as shown in the drawings and the rivets 7 and 10 are in position, it is practically impossible to gain access to the interior of the horn without ruining the same.

Secured to the back of the coil housing 11 by means of a rivet or other suitable fastening means shown at 12, and disposed within said housing, is a magnet 13 which receives its operating energy through conductors 14 having electrical connection with terminals 15 carried by the outside of the housing 11. The terminals 15 are, of course, intended to be connected with any suitable source of alternating current in a manner well known to those skilled in the art.

The flat spring or spring diaphragm 9 is provided with a central opening through which projects a bolt 16 which is riveted in position, as shown. Threaded upon the rear portion of this bolt 16 is a relatively large armature 17 disposed in close proximity to the magnet 13, this armature being secured at the desired position by means of a locking nut 18.

The sounding diaphragm 8 is provided with a central opening into which is riveted a ring 19, as shown. The bolt 16 carried by the flat spring or spring diaphragm 9 is provided with a head 20, into which is threaded a screw 21, this screw extending through the opening in the ring 19 carried by the sounding diaphragm 8. It will readily be seen that by properly adjusting armature 17 and the screw 21, the head of the screw 21 will be brought into engage-

ment with the ring 19 when the armature 17 is attracted, and so vibrate the sounding diaphragm to produce the necessary sound.

While I have illustrated my invention in the particular embodiment herein shown and described; I do not limit myself to this particular construction, but desire to claim broadly any equivalents thereof which may suggest themselves to those skilled in the art.

What I claim and desire to secure by Letters Patent is:

1. An electric horn comprising a casing, a sounding diaphragm, a spring diaphragm disposed behind the sounding diaphragm, a magnet disposed behind the sounding diaphragm, an armature connected with the spring diaphragm arranged to be actuated by the magnet, a central opening in said sounding diaphragm, and an impact member connected with the spring diaphragm passing freely through said opening and provided with a portion normally out of engagement with the sounding diaphragm but arranged to engage the same when the armature is actuated.

2. An electric horn comprising a sounding diaphragm, a magnet, an armature, a spring tending to hold said armature out of its attracted position, a hole in said sounding diaphragm, and an impact member mechanically connected with the armature extending freely through said opening, said impact member comprising a portion normally out of engagement with the sounding diaphragm but arranged to strike the same when the armature is actuated.

3. An electric horn comprising a sounding diaphragm, a spring diaphragm, said spring diaphragm being disposed behind said sounding diaphragm, a magnet disposed behind the spring diaphragm, an armature of relatively great mass carried by the spring diaphragm and the spring diaphragm alone, said armature being arranged to be attracted by said magnet, a central opening in said sounding diaphragm, and an adjustable screw carried by the spring diaphragm extending freely through said opening, said screw being provided with a head normally out of engagement with the sounding diaphragm but arranged to strike the same when the armature is attracted.

4. An electric horn comprising a casing, a sounding diaphragm, a spring diaphragm, a magnet disposed behind the spring diaphragm, an armature carried by the spring diaphragm and the spring diaphragm alone, arranged to be attracted by said magnet, a central opening in said sounding diaphragm, and an impact member carried by the spring diaphragm extending freely through said central opening, said impact member being provided with a portion normally out of engagement with the sounding diaphragm but arranged to strike the same when the armature is attracted.

In witness whereof, I hereunto subscribe my name this 16th day of June, A. D., 1913. 70
GEORGE M. WILLIS.

Witnesses:

ALBERT G. McCaleb,
AUGUST H. ARNDT.
